UNITED STATES PATENT OFFICE

HENRY V. BALL, OF CONCORD, MASSACHUSETTS, ASSIGNOR, BY MESNE ASSIGNMENTS,
TO R. HOE AND CO., INC., OF NEW YORK, N. Y., A CORPORATION OF NEW YORK

PRINTING MACHINE

Application filed May 10, 1922, Serial No. 559,790. Renewed May 2, 1930.

This invention relates to printing machines and more particularly to improvements in web-feeding mechanisms employed with such machines.

5 In the web-feeding mechanisms heretofore in use the running roll and the spare roll have not been supported and arranged so as to provide for uniting the nearly exhausted web from the running roll with the web on the 10 spare roll in the most expeditious manner. It is an object of the present invention to provide a construction and arrangement which is effective to produce a practically instantaneous union between the two webs whenever the running roll has been run down to a 15 size making it desirable to run the web from the spare roll.

The union of the two webs in the manner now practiced commercially, as well understood by those skilled in the art, is imperfect and disadvantageous in that web breakage frequently occurs. It is a further object of the present invention to provide a web-feeding arrangement of the rolls which wholly 25 obviates this danger of web breakage.

In the broader aspects of the invention these objects may be attained by any relative arrangement of the paper rolls and web-path from the running roll which will cause the 30 running path of the web to be in position to make the splice to the spare roll, at the proper time, without the necessity of shifting said web path. The preferred form of the invention for attaining these objects contemplates 35 the provision of supports for a running roll and a spare roll and a web path having such a relation to each other that as the running roll reduces its diameter, due to the running of the web, the web path approaches the spare 40 roll, and finally, at the time the running roll becomes nearly exhausted and replacement is required, comes in contact therewith or sufficiently close to effect an instantaneous union. The relative arrangement of the supports 45 and the web path is such that during the running of the web it has a movement, in direction and extent, sufficient to bring it to a position relative to the spare roll for an instantaneous union therewith when the running 50 roll is nearly exhausted. In one aspect of

the invention, the running web is caused to contact, at the proper time, with the spare roll thus positioning it for a union of the two webs without the necessity, as heretofore, of a movement of the web out of its running path. The contact with the spare roll, permitting union therewith, is made with the running web still in its normal feeding path, through a bodily movement of the web path toward the spare roll, due to the decrease in size of the running roll. Those skilled in the art will understand that actual contact is not essential since the object is to obviate the use of shifting roller mechanism and like expedients.

To the accomplishment of these objects and such others as may hereinafter appear, as will readily be understood by those skilled in the art from the following description, the invention comprises the features and combinations of parts, the preferred form of which is shown in the accompanying drawings, in which:

Figure 1 is a view, in side elevation and partly diagrammatic, of one unit of a printing machine having the improved web-feeding mechanism applied; and

Fig. 2 is a partial view, similar to Fig. 1, showing the running web at the time the running roll is nearly exhausted and a splice is to be made with the spare roll.

In the embodiment of the invention illustrated in the drawings, the printing machine frame is indicated at 10, with a diagrammatic representation of the usual assemblage of inking, plate and impression cylinders and cooperating composition rollers supported thereby, indicated generally by 12. It is sufficient for the purposes of the present application to illustrate only one unit of a printing machine, since it will be understood that the improved web-feeding mechanism will be applied to each unit in a like manner except for such changes in the location, relative to the impression cylinders, of the rollers for guiding and tensioning the web, as may be required by the construction of the frame or the arrangement of the impression cylinders thereon.

The guide and tension rollers, just referred

to, are located below the impression cylinders in the position shown in Fig. 1 for the type of press here illustrated, and are indicated by the reference characters 14 and 16. 6. Mounted on the frame 10 in a plane below the tension roller 16 is another guide roller 18. Below the guide roller 18 is a frame or bracket 20 secured to the frame 10 and adapted to receive and support in fixed position 10 two paper rolls from which the web is to be drawn successively. These two rolls are arranged on the bracket 20 one above the other, the lower roll 22 being the roll from which the web is to be drawn first, the upper roll 24 being, for the time being, a spare roll. 15. The rolls 22 and 24 have, respectively, the usual spindles 26 and 28. The bracket 20 is constructed in any convenient or usual manner to receive the ends of these spindles 20 and thus support the rolls in position to have the web withdrawn by passing from the roll to the guide and tension rollers 18, 16 and 14, and finally about the impression cylinders, in the manner illustrated in Fig. 1. It will be 25 apparent that in any embodiment of the invention it is immaterial just what is the sequence of the guide rollers between the paper roll and the impression cylinders, and that in the illustrated embodiment of the invention the essential feature of the arrangement is that the feeding path 30 of the running web, from the lower or running roll 22 to the first guide roller, be clear of the spare roll 24 during the major portion of the period required to unwind the web from the roll 22. While this may be accomplished in various ways it is conveniently accomplished by off-setting the point of support for the running roll 22 and mounting the first guide 35 roller 18 above the spare roll 24 in such a lateral position relative to the spindle 26 and at the web path of said spindle, that as the running roll 22 unwinds in a clockwise direction, viewing Fig. 1, the web feeding path 30 is clear of the spare roll 24. The lateral position of the guide roller 18 is so chosen, however, that when, or approximately when, the running roll has been so decreased in size that a union of its web with the web of the spare roll must be effected, the feeding path 30 is tangent, or substantially tangent, to the peripheral surface of the spare roll 24. 40. It will be observed, from a comparison of 55 Figs. 1 and 2, that as the lower or running roll decreases in size the normal running path of the web is automatically moved toward the upper or spare roll, the extent of this movement being so related to the unwinding 60 of the running roll that when the web is about to expire from the running roll the normal path of the web brings it against, or almost against, the spare roll. Those skilled in the art will recognize that this result gains a 65 distinct advantage in that the web is in the

required position to make the splice at the time it is necessary to make it, and furthermore is so positioned that it is unnecessary to use the complicated shifting roller mechanisms usually employed for shifting the web path from the running roll to the spare roll so as to make the paste. 70

While, as hereinbefore described, it is preferred to so arrange the web carrying and guiding rolls that the web runs at a distance 75 from the spare roll until the time arrives to make the splice, an arrangement of said elements which varies the time when the web-path is brought to pasting position relative to the spare roll is within the scope of 80 the invention as defined by the claim hereto appended.

In order to properly control the unwinding of the web from the rolls 22 and 24 an adjustable V-shaped friction pulley may be 85 applied to one end of each of the spindles 26 and 28, such mechanism being so well known in the art that it is not deemed necessary to illustrate it.

While it is preferred to employ the specific 90 construction and arrangement of parts shown and described, it will be understood that this construction is not essential except so far as specified in the claim, and may be changed or modified without departing from the 95 broader features of the invention.

What is claimed as new is:

In a web-feeding mechanism, a running 100 roll, a guide roller for the running web from said roll, a spare roll intermediate said running roll and guide roller, and fixed supports for the spindles of said rolls so related to each other that the running roll cannot be exhausted without the web-path therefrom engaging the periphery of the spare roll. 105
